BAILER

Paul Cavins, Long Beach, Calif.

Application August 22, 1935, Serial No. 37,404

7 Claims. (CL. 166—19)

The present invention relates to bailers, and particularly a brazier of the suction type wherein sand and other material which it is desired to remove from the well is drawn into the sand chamber by suction created by the relatively sudden discharge of fluid from the sand chamber into the suction chamber.

The principal object of the invention is to provide a brazier which is of relatively simple construction, and which may be formed from standard stock tubing fittings and the like.

Another object of the invention is to provide a brazier which is positive in its operation, and which is not likely to become jammed or frozen.

15 Another object of the invention is to provide a brazier in which major communication between the sand chamber and the suction chamber does not exist until an interval of time after the brazier shoe has struck well bottom or a major obstruction in the well.

20 Another object of the invention is to provide a brazier which is self-unloading, and having means to insure that the brazier will not remain jammed in loaded condition after the same is removed from the well.

25 In the drawings, which are illustrative of several forms of the invention, and in no sense restrictive,

30 Figure 1 is a vertical cross sectional view of the assembled brazier of my invention.

35 Figure 2 is an enlarged vertical sectional view of the valve assembly of my invention, showing the valve in closed position.

Figure 3 is an enlarged vertical sectional view 35 of the valve assembly of my invention, showing the valve in open position.

40 Figure 4 is a horizontal cross sectional view taken along the line 4—4 of Figure 2, showing the type of relief valve used wherever needed on the brazier.

Figure 5 is a horizontal cross sectional view taken along the lines 5—5 of Figure 2.

45 Figure 6 is a fragmentary view of the brazier in vertical section, showing the brazier shoe and means for regulating the flow and direction of flow of the sand charge into the sand chamber.

Figures 7, 8 and 9 are vertical cross sectional views of modified forms of my invention.

50 Figure 10 is a horizontal cross sectional view along the line 10—10 of Figure 7, and

Figure 11 is a horizontal cross sectional view along the line 11—11 of Figure 8.

In Figure 1, my invention is shown incorporated in a brazier of the type which is adapted 55 to be connected to a line and lowered into a well

to remove sand and the like therefrom by suction. The brazier generally comprises a closed, substantially air-tight suction chamber, a sand chamber having a shoe attached at the lower end thereof, and a valve mechanism for controlling 5 communication between said chambers.

The brazier is suspended from a suitable line by a top connecting ring or eye 12 which is carried by a threaded member 10, which is screwed upon the upper end of the top sub 1. The top sub 1 10 has a lower threaded extension which is threaded to the upper end of a tube 2, the latter being substantially twenty feet in length and forming the suction chamber 3. The top sub 1 is bored as at 4 to form a passage connecting at its lower 15 end with the suction chamber 3, said bore being closed at its upper end but provided with a suitable aperture 5 to receive a relief valve of the type shown in Figure 4.

The sand chamber is designated by the number 20 20 and is formed by a barrel comprising the tube sections 21 and 22 which are threaded together at 23. The sand chamber is in practice generally twenty feet in length, although its size may be varied as required. Tube section 22 is 25 threaded at its lower end to a sub 24, which in turn has threaded to its lower end a sleeve 25. Sleeve 25 carries at the lower end thereof a shoe 26, said shoe being open at its bottom to form an inlet 26a and is provided with additional inlet 30 apertures 26' in its side wall, the degree of opening of said apertures being adjustable by means of the vertically slid able covers 29, as shown in Figure 6. The lower end of the connector 24 is extended downwardly as at 27 to 35 form a sleeve within the tube 25, and tube 25 is equipped with outlet openings 28 adapted to be aligned with corresponding openings in the liner 27. The usual sand retaining flap valve 30 is mounted above the shoe but below the outlet 40 openings 28.

In order to insure that the pressure within the sand chamber does not become extreme when the brazier is being withdrawn from the well, a relief valve 5 such as is shown in Figure 4 is mounted 45 in a threaded opening 31 in the wall of the tube 21, which tube forms a portion of the sand chamber.

The upper end of the tube 21 is threaded to the lower end of a connecting element 33, the 50 threaded portion of said element extending down into the tube 21 as at 34, providing an interior bushing or valve member for a purpose which will later appear. The lower end of the bushing 34 is bevelled upwardly and inwardly from the tube 55

21 to provide a valve seat 35, as is most clearly disclosed in Figure 3.

The connecting element 33 is provided with a bore 33' to receive a sleeve 37, said sleeve forming an interior telescoping member for cooperation with an exterior telescoping member 38, the latter being a tube threaded at its upper end to the lower end of the hollow sub 39. The upper end of the hollow sub 39 is threaded to the lower 10 end of the suction chamber 2.

The sub 39 has an interior threaded bore 40 at its lower end, in which is secured the upper end of a hollow rod 41, said rod extending downwardly through tube 38, sleeve 37, element 33 and 15 the bushing 34, and terminating at its lower end in a piston portion 41' and an enlarged portion 42, said portions constituting a valve member. The upper end of the enlarged portion 42 is bevelled upwardly and inwardly from its outside 20 surface to form a valve seat 35' (Figure 3) for cooperation with the valve seat 35.

To cushion the telescopic action of the tube sections 37 and 38, a spring 44 is mounted between the sub 39 and the upper end of the tube 37, 25 said spring surrounding the hollow rod 41 and being within the tube section 38. The tube section 38 is provided with suitable ports to relieve any pressure which may be caused by the telescoping action.

30 Spring 44 also tends to hold the sections 37 and 38 apart and thus to maintain the valve in closed position.

The lower end of the hollow rod 41 is provided with a helical series of fluid apertures 46, which 35 extend into the interior of said rod, the interior of said rod constituting a passage 47 leading to the suction chamber 3. The lowermost of the fluid apertures 46 is disposed a predetermined distance above the valve seat 35', so that a 40 definite interval will transpire between the time when the bailer shoe hits well bottom or a major obstruction in the well, and when major communication will exist between the sand chamber 20 and the passage 47 leading to the suction 45 chamber. Major communication will exist between the chambers when one or more of the apertures 46 moves below the valve seat 35.

Within the lower part of the bore 33', a suitable packing 48 is provided around the hollow rod 41. This packing is held in place and is compressed by the sleeve 37, said sleeve being forced 50 downwardly by the action of the spring 44. While this packing serves to insure against fluid leakage upwardly around the hollow rod 41, the 55 relatively loose fit of the sleeve 37 within the bore 33' will provide a relief valve which will operate if the bailer becomes jammed at well bottom and if the other relief valves fail to function.

In Figures 1 and 2, the bailer is shown in the 60 position which it will assume as it is being lowered into the well. It will be noted that as the bailer is being lowered into the well, the sand chamber is suspended from the suction chamber, the point of suspension being where the seat 35' 65 of the valve member 42 encounters the seat 35 of the bushing or valve member 34. When the bailer is in this condition, the suction chamber 3 is sealed at its lower end by the valve and at its upper end by the sub 1, the chamber thus being 70 air-tight and at substantially atmospheric pressure.

By reason of the fact that the weight of the sand chamber is carried where seat 35' encounters seat 35, it is obvious that the valve 75 member 42 will be held tightly against the valve

member 34 to seal the fluid way between the suction and sand chambers, and there is little possibility of jars caused by minor obstructions encountered by the shoe in the well tube moving the valve members relatively to one another to 5 break the seal. Even if an obstruction in the well at a point where it is not desired to draw sand is encountered with such force as to break the seal, a major flow of fluid from the suction chamber to the sand chamber will not be permitted, 10 by reason of the fact that the lower end or piston 41' of the rod 41 fits tightly enough within the bushing or valve member 34 to materially restrict flow of fluid through the passage provided by the bushing. It will further be noted that 15 before premature major opening of the fluid way can result, it will be necessary not only to break the seal provided by the valve members 34 and 42, but in addition the suction chamber must move downwardly a sufficient distance to position the initial fluid aperture 46 below the edge of the seat 35. Furthermore, as the bailer is being lowered into the well, the pressure exerted by the spring 44 also tends to assist the pressure in the sand chamber in maintaining the valve in 20 sealed condition.

Thus, it will be seen that I have provided a bailer which insures against premature opening of the suction-sand chamber fluid way. It may be said that this fluid way is controlled by a primary and a secondary valve, the primary valve being constituted by the sealing surfaces 35 and 35', and a secondary valve being formed by the cooperation of the piston portion 41' of the hollow rod 41 and the apertures 46, with the interior 35 surface of the bushing 34.

When the bailer shoe strikes well bottom or a major obstruction in the well, the sand chamber, including the tube 21 and the attached bushing or valve member 34, will be suddenly arrested in 40 its downward movement. This will cause a slackening of the tension on the lowering line, thus permitting the suction chamber to move downwardly by its own weight.

When the suction chamber moves downwardly, 45 the seal provided by the seating surfaces 35 and 35' will first be broken, followed by an interval during which the piston 41' will restrict the upward passage of fluid through the fluid way formed by the bushing 34. During this movement, some of the fluid which passes upwardly between the inner surface of the bushing 34 and the surface of the piston 41' will pass in through the apertures 46 into the suction chamber 47. If the bailer has struck well bottom, and the bailer shoe has embedded itself into the sand, the sand chamber 20 will be closed at its lower end, but will be in slight communication with the suction chamber when the seal provided by the engaging surfaces 35 and 35' is broken. That is, when the 60 hollow rod 41 begins to move downwardly, some fluid will pass between the surface of the piston 41' and the inner surface of the bushing 34 even before the lowermost port 46 gets below the valve seat 35. As stated above, if the bailer shoe is embedded in the sand, the lower end of the sand chamber 20 will be closed, and this initial flow of fluid from the sand to the suction chamber will 65 reduce the pressure in the former chamber, thus assisting by the pressure reduction in moving the 70 hollow rod 41 downwardly until the ports 46 are below the valve seat 35. It will be understood that, while this initial flow of fluid will reduce the upward pressure on the lower end of the enlarged head 42, the downward pressure on the 75

top of the bailer, which is the well pressure, will remain the same, and therefore there will be a pressure difference which will tend to move the hollow rod downwardly to effect a major opening 5 of the fluid way.

When the lowermost fluid aperture 46 descends to a point below the valve seat 35, major communication will exist between the sand chamber and the suction chamber, thus permitting a rush of 10 fluid into the suction chamber, the latter being at relatively low atmospheric pressure, while the sand chamber is at relatively high well pressure. The passage of fluid from the sand chamber to the suction chamber will create sufficient suction 15 in the sand chamber to draw sand through the bottom opening 26a in the shoe and through the ports 26', if the latter are open, past the flap valve 30 and into the sand chamber 20. This inflow of sand and fluid will cause the pressure in the 20 suction chamber 3 to be equalized with the pressure in the sand chamber 20, the latter being the pressure caused by the weight of the head of fluid standing idle in the well. As the bailer may be used in wells of such depth as to cause a high 25 pressure to be built up in the suction chamber 3, said chamber is provided with the relief valve at 5 to function in the well known manner as the bailer is being elevated from the well. By providing such a relief valve, pressure in the suction 30 chamber which might become dangerous as the bailer is lifted from the well is relieved during elevation, so that when the bailer reaches the surface, the pressure in the suction chamber will not be dangerously high.

35 It will be noted that by reason of the helical disposition of the fluid ports 46, the area of the opening between the sand chamber and the suction chamber will be progressively increased during the last stage of movement of the piston 41' 40 downwardly, until finally the complete area of said openings is exposed for the passage of fluid.

By this construction and operation, a bailer is provided which is precluded from premature opening, and, furthermore, the fluid way between the 45 sand chamber and the suction chamber is kept restricted for a sufficient interval after the shoe has struck well bottom to insure that the shoe takes a firm bite in the sand, and thus the bailer is not likely to operate faultily and draw in only liquid. Furthermore, the progressive fluid opening provided by the disposition of the apertures 46 insures that the bailer shoe has taken a solid 50 bite in the sand before full communication is established between the sand chamber and the suction chamber. On the other hand, the full 55 force of impact of the bailer on a well bottom is availed of in opening the valve, as this force is utilized in starting the piston 41' toward its open position, although, as stated above, major opening 60 of the fluid way is delayed until termination of a predetermined time.

Obviously, the hollow rod 41 may be removed and another rod with ports 46 placed at different 65 positions with respect to the valve seat 35 may be provided in order to vary the interval of delay in the major opening of the valve. Similarly, the lowermost of the ports 46 might be plugged in order to increase the interval of delay, or vary 70 the area of fluid passage.

70 After the sand chamber 20 has become filled with sand, the bailer may be lifted from the well in the usual manner, the flap valve 30 serving to confine the sand within the sand chamber during this upward movement. At the surface of the 75 ground, the sand may be removed from the sand

chamber 20 through the outlet ports 28 in the manner disclosed in the patent to Omar A. Cavins, No. 1,917,211, July 4, 1933, the bailer being rested on its shoe resulting in the opening of the suction-sand chamber valve by reason of the weight 5 of the suction chamber. In this connection, the built-up pressure in the suction chamber 3 will assist in the unloading of the sand.

In Figure 7 a modification of the invention is shown wherein a hollow rod 50, having a valve 10 member 51 at the lower end thereof, extends the entire length of the suction chamber 52 and beyond the upper end thereof as at 53 where it is threaded into a top sub 54 which may be connected with the lowering line in any suitable 15 manner. The upper end 53 of the hollow rod 50 is shown interiorly screw threaded to receive a fitting 55 having a passage 56 therethrough, said 20 passage being controlled by a suitable spring pressed relief valve 51, the relief being accomplished through the side openings 58 in the top sub 54 leading from the relief valve.

In lieu of the enclosed spring 44 shown in the preferred embodiment of Figure 1, an outside 25 spring 60 is utilized in the modified construction of Figure 7, this spring being mounted around the portion 53 of the hollow rod 50, and held at its ends between the lower face of the top sub 54 and the top of the suction chamber. Where the hollow rod passes out through the top of 30 the suction chamber, it may be surrounded by a packing 62 compressed within the top cover 63 by the gland 63'.

The portion of the hollow rod 50, which is located within the suction chamber 52, is provided with a plurality of apertures 64 which connect the interior of said rod with the suction chamber. The lowermost of these apertures are adapted to move downwardly below the valve seat when the bailer is arrested in the well, as discussed in connection with the preferred embodiment, while the uppermost apertures 64 permit fluid to flow from within the hollow rod out into the suction chamber 52. Thus, while the hollow rod extends throughout the length of the suction chamber, by reason of the fact that it is in open communication with the suction chamber at all times, its interior forms a part of said chamber, and the volume of the suction chamber is not materially decreased by this arrangement. 50

In Figure 8 a construction similar to that of Figure 7 is shown, except that instead of using apertures in the hollow rod to pass below a valve seat carried by the sand chamber, a portion 68 of the hollow rod 67 is of reduced diameter between 55 the points 68', this reduced portion being of sufficient length to bridge the bushing 69 which carries the valve seat 66 when the tool strikes a major obstruction in the well, to permit fluid to flow up through the fluid way formed by the interior of said bushing and into the sand chamber 10. As in the embodiment shown in Figure 7, the hollow rod may be provided with apertures 71, which maintain communication at all times between the interior of said rod and the suction 60 chamber. Thus, as in the embodiment of Figure 7, while the hollow rod extends throughout the length of the suction chamber, it does not diminish the volume of said chamber because of the connecting apertures 71. 70

While I have shown in Figure 8, a hollow rod 67 reduced in diameter between the points 68', and one having apertures 71 therein to permit constant communication between the interior of the rod and the suction chamber, this embodiment of 75

the invention may be modified by making the rod 67 solid but with the portion of reduced diameter 68, or said rod may be hollow but not provided with the apertures 71 connecting the interior of the same with the suction chamber. In this modification of the embodiment, the valve 73 (hereinafter described) at the lower end of the rod would be dispensed with, and the lower end of said rod would be of the form shown at 51 in Figure 7.

The suction chamber may be provided with a suitable relief valve 72 which functions in an identical manner with the relief valve mounted in the aperture 5 in the embodiment of Figure 1.

15 In the embodiment of Figure 8, I have shown an additional relief valve 73, spring pressed upwardly against its seat to close an opening 74 from the sand chamber 75 to the interior of the hollow rod. This valve provides a relief from the suction chamber to the sand chamber, to supplement the protection afforded by the relief valve 72, in that this valve 73 will operate when the bailer is elevated from the well to relieve dangerous pressures from the suction chamber into the sand chamber, in case the relief valve 72 fails to function to relieve the suction chamber to the outside of the tool.

As discussed above in connection with the preferred embodiment of Figure 1, the bailer is emptied on the well platform by placing the weight of the tool on the shoe to open the valve between the suction chamber and the sand chamber, with the sand chamber discharge ports 28 in open condition. It sometimes happens that due to sand getting in the sliding surfaces of the tool, or more usually because of bending of parts of the tool in the well due to their great length, that the weight of the suction chamber will not be sufficient to move the hollow rod downwardly to open the valve between the suction chamber and sand chamber, in order that the pressure in the former may assist in driving the contents of the sand chamber out through the outlet ports 28. In this event, the relief valve 73 may be relatively weakly held against its seat by adjustment of the retaining screw 76, and the pressure within the suction chamber and the hollow rod will be sufficient to open the valve and pass down into the sand chamber 75 and assist in clearing the same, even though the main valve between the suction and sand chambers is not opened by the weight of the former chamber.

If the lower part of the sand chamber becomes clogged, so that pressure in the upper part thereof remains high enough after the outlet ports 28 have been opened to restrain the hollow rod from moving downwardly when it is desired to unload the bailer, the relief valve 73, which is only lightly held upon its seat, will open under the higher pressure existing in the suction chamber to permit the fluid therein to flow into the upper part of the sand chamber and clear the same and drive the sand and other material out through the outlet ports. It will be apparent that the relief valve 73 will make possible this unloading operation under the conditions discussed above, even though pressure in the sand chamber due to clogging prevents the downward movement of the hollow rod.

70 While I have shown the relief valve in the lower end of the hollow rod associated only with the embodiment of Figure 8, it is obvious that this relief valve may be used in association with any of the other embodiments as desired.

75 In the embodiment of Figure 8, I have shown

a construction wherein a spring is used corresponding to the spring 60 of the embodiment of Figure 7. While the use of such a spring is desirable and is preferred, these bailers may be operated with reasonable efficiency without the use 5 of a spring.

In Figure 9, a barrel 80 is disclosed which defines a sand chamber 81, the upper end of said barrel being partially closed as at 82, but recessed to permit passage therethrough of the hollow 10 rod 84. Between the top of the barrel and the bushing 85, which forms the valve seat 86, suitable packing 87 is provided to maintain the seal of the suction and sand chambers. In this construction, the upper end of the hollow rod is secured to the lower end of a barrel 88 which forms the suction chamber. The construction of this embodiment will function without the provision of a spring to assist in holding the valve on its seat, but, as stated above, a spring may be used 15 20 as desired.

Obviously, various changes of the constructions shown herein may be made without departing from the range of the invention.

I claim:

1. In a suction bailer, a barrel defining a sand chamber, a closed substantially air-tight suction chamber, a valve seat carried by said barrel, a valve member adapted to engage said seat to seal said suction chamber from said sand chamber, 30 said valve member having a stem, a spring for maintaining said valve in sealing engagement with said seat when the bailer is being lowered into the well, said stem being adapted for telescoping movement with respect to said barrel 35 against the force of said spring to move said valve from its seat and break said seal when the bailer encounters an obstruction in the well, and means carried by said stem for effecting major communication between said chambers after said 40 seal is broken, said means being positioned on said stem for effecting major communication between said chambers after an appreciable movement of said stem with respect to said barrel, whereby the drawing of a charge into the bailer 45 is delayed after the same encounters an obstruction in the well.

2. In a suction bailer, a barrel defining a sand chamber adjacent the lower end of the bailer, a closed substantially air-tight suction chamber 50 above said sand chamber, said barrel carrying a valve seat and having a bore above said seat, a valve member adapted to engage said seat to seal said suction chamber from said sand chamber, said valve member having a stem above 55 the same mounted for sliding movement in said bore, a spring for maintaining said stem in an upper position with said valve in sealing engagement with said seat when the bailer is being lowered into the well, said stem being adapted 60 for downward movement in said bore against the force of said spring to move said valve from its seat and break said seal when the bailer encounters an obstruction in the well, and means carried by said stem above said valve member 65 for opening major communication between said chambers after said seal is broken, said means being spaced an appreciable distance above said valve member for opening major communication between said chambers when said stem moves 70 downwardly in said bore a distance sufficient to expose said means below said valve seat, whereby the drawing of a charge into the bailer is delayed after the same encounters an obstruction in the well.

3. In a suction bailer, a barrel defining a sand chamber adjacent the lower end of the bailer, a closed substantially air-tight suction chamber above said sand chamber, said barrel carrying a valve seat and having a bore above said seat, a valve member adapted to engage said seat to support said barrel and to seal said suction chamber from said sand chamber, said valve member having a stem above the same mounted for sliding movement in said bore, said stem being connected with the bailer lowering line when the bailer is being lowered into the well, a spring for maintaining said valve in sealing engagement with said seat when the bailer is being lowered into the well, said stem being adapted for downward movement in said bore against the force of said spring to move said valve from its seat and break said seal when the bailer encounters an obstruction in the well with consequent slackening of the lowering line, and means carried by said stem above said valve for opening major communication between said chambers after said seal is broken, said means being spaced an appreciable distance above said valve member to open major communication between said chambers when said stem moves downwardly in said bore a distance sufficient to expose said means below said valve seat, whereby the drawing of a charge into the bailer is delayed after the same encounters an obstruction in the well.
4. In a suction bailer, a barrel defining a sand chamber adjacent the lower end of the bailer, a closed substantially air-tight suction chamber above said sand chamber, said barrel carrying a valve seat and having a bore above said seat, a valve member adapted to engage said seat to seal said suction chamber from said sand chamber, said valve member having a hollow stem above the same mounted for sliding movement in said bore, the interior of said stem being in communication with said suction chamber, a spring for maintaining said stem in an upper position with said valve in sealing engagement with said seat when the bailer is being lowered into the well, said stem being adapted for downward movement in said bore against the force of said spring to move said valve from its seat and break said seal when the bailer encounters an obstruction in the well, said stem having an inlet port through the wall thereof spaced above said valve for opening major communication between said chambers after said seal is broken, said port being spaced an appreciable distance above said valve member to open major communication between said chambers when said stem moves downwardly in said bore a distance sufficient to expose said port below said valve seat, whereby the drawing of a charge into the bailer is delayed after the same encounters an obstruction in the well.
5. In a suction bailer, a casing including a sand chamber adjacent the lower end thereof, and a closed substantially air-tight chamber above said sand chamber, a valve seat carried by said casing including a sealing surface and a bore above the same, a valve stem of substantial weight extending through said suction chamber and in slidable engagement with said bore and having a valve member at its lower end to engage the sealing surface of said seat, a spring mounted on said casing for maintaining said stem in an upper position with said valve member in sealing engagement with the sealing surface of said seat when the bailer is being lowered into the well, said stem being adapted to move downwardly with respect to said casing by its own weight when the bailer encounters an obstruction in the well, and means on said stem spaced an appreciable distance above said valve member for opening major communication between said chambers when said stem moves downwardly in said bore a distance sufficient to expose said means below said valve seat, whereby the drawing of a charge into the bailer is delayed after the same encounters an obstruction in the well.
6. In a suction bailer, a casing including a sand chamber adjacent the lower end thereof, and a closed substantially air-tight chamber above said sand chamber, a valve seat carried by said casing including a sealing surface and a bore on said casing above the same, a hollow valve stem of substantial weight extending through said suction chamber and in slidable engagement with said bore and having a valve member to engage the sealing surface of said seat at its lower end, a spring mounted on said casing for maintaining said valve in an upper position with said valve member in sealing engagement with the sealing surface of said seat when the bailer is being lowered into the well, the interior of said stem being in communication with said suction chamber and said stem being adapted to move downwardly with respect to said casing by its own weight when the bailer encounters an obstruction in the well, said stem having a port through the wall thereof spaced an appreciable distance above said valve member for opening major communication between said chambers when said stem moves downwardly in said bore a sufficient distance to bring said port below said valve seat, whereby the drawing of a charge into the bailer is delayed after the same encounters an obstruction in the well.
7. In a suction bailer, a casing including a sand chamber adjacent the lower end thereof, and a closed substantially air-tight chamber above said sand chamber, a valve seat carried by said casing including a sealing surface, and a restricted bore on said casing above said seat between said chambers, a valve stem of substantial weight extending through said suction chamber and in slidable engagement with said bore and having a valve member at its lower end to engage the sealing surface of said seat, a spring mounted on said casing for maintaining said stem in an upper position with said valve member in sealing engagement with the sealing surface of said seat when the bailer is being lowered into the well, said stem being adapted to move downwardly with respect to said casing by its own weight when the bailer encounters an obstruction in the well, said stem having a reduced portion spaced an appreciable distance above said valve member and of sufficient extent to breach the restricted bore between said chambers, said reduced portion being adapted to open major communication between said chambers when said stem moves downwardly in said bore a sufficient distance to expose the lower end of said reduced portion below said valve seat, whereby the drawing of a charge into the bailer is delayed after the same encounters an obstruction in the well.

PAUL CAVINS.
